UNITED STATES PATENT OFFICE.

JOHN STANLEY VOORHEES, OF NEW YORK, N. Y.

INTERCHANGEABLE LOCKING-BORDER.

No. 919,094.

Specification of Letters Patent. Patented April 20, 1909.

Application filed October 30, 1908. Serial No. 460,280.

To all whom it may concern:

Be it known that I, JOHN STANLEY VOORHEES, a citizen of the United States, and a resident of the city of New York, borough of Manhattan, in the county and State of New York, have invented a new and Improved Interchangeable Locking-Border, of which the following is a full, clear, and exact description.

- 10 The invention relates to printing and its object is to provide a new and improved interchangeable locking border, arranged to readily connect the border pieces with each other, and to securely hold the same in place, 15 to allow of conveniently interchanging and connecting border pieces of different length, for forming narrow or wide borders for columns of different width and for long or short matter to be inclosed by the border, 20 the arrangement also serving to allow the set up type and its border to be set aside for future use without requiring tying of the border by the use of cords, bands or the like.

The invention consists of novel features 25 and parts and combinations of the same, which will be more fully described herein-after and then pointed out in the claims.

A practical embodiment of the invention is represented in the accompanying drawings forming a part of this specification, in 30 which similar characters of reference indicate corresponding parts in all the views.

Figure 1 is a plan view of the improvement as arranged for a narrow column, parts being 35 in section; Fig. 2 is a plan view of the same arranged for a wide column; Fig. 3 is a perspective view of one end of a border member and the joint fastener in position thereon; Fig. 4 is a side elevation partly in section, of 40 one end of one of the border pieces; Fig. 5 is an inverted plan view of the improvement as arranged for mitered border pieces.

The border illustrated in Fig. 1 consists of border pieces A, A' and A², A³, removably 45 fastened together at the corners by joint fasteners B, one for each corner, and each joint fastener being made from a single piece of sheet metal bent to provide the members B', B² standing at a right angle to each other, 50 the free ends of the members B', B² terminating in angular lugs B³, B⁴ bent inwardly at right angles to the corresponding members B' and B², as plainly indicated in Fig. 3.

The border pieces A, A', A² and A³ are 55 provided on the top with a suitable printing face, and the ends of the border pieces A

and A' are provided at the under side with longitudinally-extending slots C and similar slots C' are formed at the under side of the ends of the border pieces A², A³, as plainly 60 indicated in Figs. 1 and 3. The cross slots C² intersecting the longitudinal slots C are formed in the border pieces A and A', and two cross slots C³, C⁴ intersecting the corresponding longitudinal slots C' are formed at each 65 end of each of the border pieces A², A³. Now in order to assemble the border pieces A, A', A² and A³, the ends of the border pieces A, A' are abutted against the inner faces of the border pieces A², A³, as plainly shown in 70 Fig. 1, and with the border pieces arranged on a table upside down, and then a joint fastener B is applied to each corner of the border by placing the joint fastener in position so that its members B', B² engage the 75 longitudinal slots C', and the angular lugs B³, B⁴ engage the cross slots C², C³, the member B' also passing through the cross slot C⁴, as will be readily understood by reference to Figs. 1 and 3. The slots are of such depth 80 and the side members B', B² are of such length that when the joint fasteners B are pushed in place their lower faces are flush with the under side of the border members A, A', A², A³ (see Fig. 3).

In practice, the slots in the border pieces are cut by rotary cutters, as indicated in Fig. 4, and the side members B', B² are preferably beveled so as to fit the segmental slots or cuts made by the rotary cutters. Now 90 by the arrangement described, the borders A, A', A² and A³ are securely fastened together at the corners by joint fasteners, which do not in the least interfere with the printing faces of the border members, and 95 which can be readily rotated whenever it is desired to disassemble the border.

It will be seen that the border members of different length when provided with the slots referred to can be readily fastened together by the joint fasteners B; for instance, as shown in Fig. 2, the same border pieces A and A' are connected with border members A⁴, A⁵ of greater length than the border members A², A³, so as to form a border for 100 a wider column. In a like manner several border pieces A, A' may be fastened to the border members A², A³ or the border members A⁴, A⁵, for inclosing type to form a 105 short column.

In the modified form shown in Fig. 5, the adjacent border members A⁶, A⁷ are fitted 110

together at their ends at a miter, and in this case the slot C⁴ is omitted, but otherwise the fastener B is applied in the same manner for fastening the border members together. In 5 each of the cases mentioned the joint fasteners B are alike. By fastening the border pieces together in the manner described, the border with the type held therein can be readily set aside for future use without tying 10 the border by the use of bands, cords or the like. Although I have shown the fasteners B particularly applied to border pieces for containing type for surrounding electro-plates and the like, it is evident that the 15 joint fasteners may be used for fastening the members of picture frames, signs and the like together.

Having thus described my invention, I 20 claim as new and desire to secure by Letters Patent:

1. In combination, a border having sides and ends abutting one on the other at the terminals, each of the sides and ends having longitudinal and transverse slots at the 25 underside at the terminals of the said sides and ends, the transverse slots intersecting the said longitudinal slots, and angular joint fasteners engaging the said longitudinal slots and having integral angular lugs en- 30 gaging the said cross slots, the undersides of the said joint fasteners being flush with the undersides of the said sides and ends.

2. A printer's interchangeable locking border, comprising separate and inter- 35 changeable border sides and border ends

abutting one on the other at the terminals and each of the said sides and ends being provided with a printing face and with longitudinal and transverse slots at the under side at the terminals of the said sides and 40 ends the said transverse slots intersecting the said longitudinal slots, and angular joint fasteners engaging the said longitudinal slots and having integral angular lugs en- 45 gaging the said cross slots, the under sides of the said joint fasteners being flush with the under sides of the said sides and ends.

3. An interchangeable locking border, comprising border sides, border ends, and a joint fastener for removably connecting 50 the adjacent ends of the said sides and ends, the border sides and ends having their terminals provided with longitudinally-extending slots and one terminal at each corner having a cross slot and the adjacent terminal 55 having spaced cross slots, the said joint fastener being made from a single piece of sheet metal bent to form right angle members for engagement with the said longitudinal slots and with the outermost cross slot, the said 60 joint fastener terminating in inwardly-extending lugs for engagement with the remaining cross slots.

In testimony whereof I have signed my name to this specification in the presence of 65 two subscribing witnesses.
